(57) **CLAIM**

The ornamental design for a vehicle front fender, as shown and described.

DESCRIPTION

FIG. 1 is a front perspective view of a vehicle front fender showing our new design;

FIG. 2 is a side view thereof;

FIG. 3 is a front view thereof;

FIG. 4 is a rear view thereof;

FIG. 5 is a top view thereof; and,

FIG. 6 is a bottom view.

It will be understood that the broken lines shown in the drawings illustrate portions of the vehicle front fender that form no part of claimed design.
